(57) **CLAIM**

The ornamental design for an absorbent pad as shown and described.

DESCRIPTION

FIG. 1 is a top perspective view of an absorbent pad.

FIG. 2 is a top plan view of the absorbent pad.

FIG. 3 is a bottom plan view of the absorbent pad; and,

FIG. 4 is a left side plan view of the absorbent pad.

The broken lines in the figures show features of the absorbent pad that form no part of the claimed design.

1 Claim, 4 Drawing Sheets
